UNITED STATES PATENT OFFICE.

JOHN ROGERS FLANNERY, OF PITTSBURGH, PENNSYLVANIA, AND WILLIAM McCLINE WILSON, OF CHICAGO, ILLINOIS, ASSIGNEES TO FLANNERY BOLT COMPANY, OF PITTSBURGH, PENNSYLVANIA.

TESTING STAY BOLTS HAVING TELLTALE HOLES.

Application filed March 18, 1921. Serial No. 453,220.

To all whom it may concern:

Be it known that we, JOHN ROGERS FLANNERY and WILLIAM M. WILSON, citizens of the United States, and residents of Pittsburgh and Chicago, in the counties of Allegheny and Cook and States of Pennsylvania and Illinois, respectively, have invented certain new and useful Improvements in Testing Stay Bolts Having Telltale Holes; and we do hereby declare the following to be a full, clear, and exact description of the invention, such as will enable others skilled in the art to which it appertains to make and use the same.

15 This invention relates to improvements for testing staybolts having tell-tale holes. In the construction of staybolts for boilers, it is necessary that the structure shall be such as to admit of inspection to determine whether the bolts have become fractured. Various means have been resorted to for accomplishing this,—among which may be mentioned, the removal of a cap employed normally to enclose the bolt head 25 and its bearing, so that access may be had to the bolt. Such method to accomplish the testing of the bolts is very tedious and expensive when it is remembered that many millions of staybolt structures of this type 30 are now in use and that each boiler construction employs a very large number of these staybolts.

In an effort to avoid necessity for removing the caps for inspection purposes it has 35 been proposed to provide staybolts for boilers with tell-tale holes, so that in the event of fracture of the bolt water and steam entering such hole would denote the fractured condition of the bolt. When the 40 tell-tale hole is closed at the headed end of the bolt and open at the inner or fire-box end, soot, scale or other foreign solid matter is liable to enter the tell-tale hole and thus clog the same, and to avoid this, temporary plugs have been inserted into the 45 inner end of the tell-tale hole. Such temporary plugs will serve to exclude the entrance of solid substances from the fire-box, but it is possible that in some instances especially when a bolt becomes but slightly fractured, sediment contained in the water 50 of the boiler, might enter, with water and steam, through the opening formed by the fracture and accumulate within the tell-tale

hole,—and there may be a possibility of such sediment so closing the slight fracture as to preclude the entrance of sufficient steam and water into the tell-tale hole to be readily detected by an inspector upon removing the temporary plug at the inner end of the tell-tale hole.

The object of our present invention is to provide for the testing of staybolts having tell-tale holes, in such manner that the inspector may determine with certainty whether a bolt has become fractured, however small the fracture may be, by ascertaining not only whether the tell-tale hole contains water or steam, but also whether said hole contains an accumulation of sediment which might have entered said hole through a fracture in the bolt or otherwise.

With this object in view, the invention consists in certain novel features as herein-after set forth and pointed out in the claims.

In the accompanying drawings, Figure 1 is a sectional view of a staybolt illustrating one embodiment of our invention; Figure 2 is a view of a testing implement which may be employed, and Figure 3 shows another embodiment of the invention.

1 represents a staybolt of the "flexible" type, having a rounded head 2 forged at the outer end of its body portion. After the forged head 2 shall have been formed a tell-tale hole will be formed by drilling continuously from one end of the bolt into or through the headed end thereof. In the construction shown in Figure 1 the longitudinal bore which forms the tell-tale hole 3 is drilled throughout the full length of the bolt including its headed portion, and in order that the tell-tale hole may be made to terminate within the head 2 (and therefore beyond every portion of the bolt which might be liable to fracture), we may insert a plug or closure 5 into the portion of the bore which extends through the head. This plug or closure may be either permanent or temporary. Instead of drilling the bore entirely through the bolt body and its head and closing the outer end of said bore with a plug as above described, the drilling of the bore may be made to terminate within the head 2, as indicated at 6, Figure 3.

Within the outer end portion of the tell-tale hole which is located within the head 2 of the bolt, a material 7 is located. When

the construction shown in Figure 1 is employed, the material 7 may be first inserted into the bore so as to become disposed within the head 2, and then the plug 5 may be inserted into the outer end of the bore. When the construction of bolt shown in Figure 2 is used, the material 7 may be forced through the bore from the inner end thereof so that it will become disposed in the outer end of said bore within the head 2. The inner or fire-box end of the bore or tell-tale hole will be closed by a removable or temporary plug 8.

The material 7 above referred to will be such as will color, discolor or permit portions of its mass to become attached to a testing implement, 9,—such, for example, as a rod or wire having a serrated end, when the same is inserted into the bore and thrust against such material. As one example of a material 7 which might be employed we may mention a mixture of talcum powder, silicate of soda and a coloring matter, such as vermillion. When it is desired to test the bolt without removing the cap of the structure the inspector will remove the plug 8 at the inner end of the bore or tell-tale hole 3, and if no discharge of water or steam from said hole occurs (which discharge would at once indicate a ruptured condition of the bolt), he will thrust the testing implement 9 into the bore. If a small fracture has occurred in the bolt, which would permit the entrance and accumulation of sediment, the implement 9 will encounter such sediment and this would indicate to the inspector that the bolt is imperfect. On the other hand, should the inspector be able readily to pass the testing rod or wire through bore until it encounters the material 7, such material will be caused by turning the rod or wire to

adhere to the latter and change the appearance of the end of the same, which will indicate to the inspector (when he withdraws said rod or wire) that the portion of the bore within the head had been reached and thus denote (by the absence of sediment in the bore) that the bolt is perfect.

Having fully described our invention 50 what we claim as new and desire to secure by Letters-Patent, is:—

1. A staybolt having a tell-tale hole extending from one end of the bolt axially thereof and closed at its other end, and indicating means at said closed end only of said hole for cooperation with a testing implement, substantially as described. 55

2. A staybolt having a tell-tale hole extending from one end of the bolt axially 60 thereof and closed at its other end, and indicating means at said closed end only of said hole adapted to color the end of a testing implement inserted in said hole, substantially as described. 65

3. The method of testing a staybolt having a tell-tale hole extending from one end of the bolt axially thereof and closed at its other end, comprising placing within said hole at said closed end thereof an indicating material adapted to affect a testing implement when the latter is brought into contact therewith, inserting a testing implement into said hole and moving it to the limit of its movement therein, and noting 70 whether the implement has been affected by the indicating material, substantially as described. 75

In testimony whereof I have signed this specification.

JOHN ROGERS FLANNERY.

In testimony whereof I have signed this specification.

WILLIAM McCLINE WILSON.

the construction shown in Figure 1 is employed, the material 7 may be first inserted into the bore so as to become disposed within the head 2, and then the plug 5 may be inserted into the outer end of the bore. When the construction of bolt shown in Figure 2 is used, the material 7 may be forced through the bore from the inner end thereof so that it will become disposed in the outer end of said bore within the head 2. The inner or fire-box end of the bore or tell-tale hole will be closed by a removable or temporary plug 8.

The material 7 above referred to will be such as will color, discolor or permit portions of its mass to become attached to a testing implement, 9,—such, for example, as a rod or wire having a serrated end, when the same is inserted into the bore and thrust against such material. As one example of a material 7 which might be employed we may mention a mixture of talcum powder, silicate of soda and a coloring matter, such as vermillion.

When it is desired to test the bolt without removing the cap of the structure the inspector will remove the plug 8 at the inner end of the bore or tell-tale hole 3, and if no discharge of water or steam from said hole occurs (which discharge would at once indicate a ruptured condition of the bolt), he will thrust the testing implement 9 into the bore. If a small fracture has occurred in the bolt, which would permit the entrance and accumulation of sediment, the implement 9 will encounter such sediment and this would indicate to the inspector that the bolt is imperfect. On the other hand, should the inspector be able readily to pass the testing rod or wire through bore until it encounters the material 7, such material will be caused by turning the rod or wire to

adhere to the latter and change the appearance of the end of the same, which will indicate to the inspector (when he withdraws said rod or wire) that the portion of the bore within the head had been reached and thus denote (by the absence of sediment in the bore) that the bolt is perfect.

Having fully described our invention what we claim as new and desire to secure by Letters-Patent, is:—

1. A staybolt having a tell-tale hole extending from one end of the bolt axially thereof and closed at its other end, and indicating means at said closed end only of said hole for cooperation with a testing implement, substantially as described.

2. A staybolt having a tell-tale hole extending from one end of the bolt axially thereof and closed at its other end, and indicating means at said closed end only of said hole adapted to color the end of a testing implement inserted in said hole, substantially as described.

3. The method of testing a staybolt having a tell-tale hole extending from one end of the bolt axially thereof and closed at its other end, comprising placing within said hole at said closed end thereof an indicating material adapted to affect a testing implement when the latter is brought into contact therewith, inserting a testing implement into said hole and moving it to the limit of its movement therein, and noting whether the implement has been affected by the indicating material, substantially as described.

In testimony whereof I have signed this specification.

JOHN ROGERS FLANNERY.

In testimony whereof I have signed this specification.

WILLIAM McCCLINE WILSON.

Certificate of Correction.

It is hereby certified that in Letters Patent No. 1,567,721, granted December 29, 1925, for an improvement in "Testing Stay Bolts Having Telltale Holes," the name of the second-mentioned patentee was erroneously written and printed as "William McCline Wilson," whereas said name should have been written and printed as "William McCleare Wilson; and that the said Letters Patent should be read with this correction therein that the same may conform to the record of the case in the Patent Office.

Signed and sealed this 9th day of February, A. D. 1926.

[SEAL.]

WM. A. KINNAN,
Acting Commissioner of Patents.

Certificate of Correction.

It is hereby certified that in Letters Patent No. 1,567,721, granted December 29, 1925, for an improvement in "Testing Stay Bolts Having Telltale Holes," the name of the second-mentioned patentee was erroneously written and printed as "William McCline Wilson," whereas said name should have been written and printed as *William McCleave Wilson*; and that the said Letters Patent should be read with this correction therein that the same may conform to the record of the case in the Patent Office.

Signed and sealed this 9th day of February, A. D. 1926.
